UNITED STATES PATENT OFFICE.

FRANK B. BIGELOW, OF DETROIT, MICHIGAN.

STOKER.

1,198,316.

Specification of Letters Patent. Patented Sept. 12, 1916.

Application filed July 19, 1915. Serial No. 40,536.

To all whom it may concern:

Be it known that I, FRANK B. BIGELOW, a citizen of the United States, residing at Detroit, in the county of Wayne and State 5 of Michigan, have invented certain new and useful Improvements in Stokers, of which the following is a specification.

My invention pertains to improvements in stokers in general, but refers more specifically to features of novelty and advantage 10 in continuous-feed, sectional coal-pushers or fuel-stokers.

In the furnaces of the V-shape Murphy type, and of other styles, a plurality of reciprocating or sliding stoker-boxes have been employed to feed the coal to the furnace-grates, and it has been customary to advance them simultaneously and retract them in the same manner, although it has been usual to 20 provide such pushers with differential actions, that is, some would have greater strokes or ranges of movement than others.

One of the leading features of the present invention is the production of a fuel-feeding or stoking mechanism of this general type which will produce a substantially-continuous fuel feed or coal advance.

A further object of the invention is the production of an appliance of this character 30 which shall be composed of relatively few parts, economical to manufacture, and unlikely to become deranged in service.

In order that those skilled in this art may have a full and complete understanding of 35 the invention and the manner in which these and other objects are obtained, I have illustrated a preferred and desirable embodiment of the invention in the accompanying drawings forming a part of this specification and 40 to which reference should be had in connection with the following detailed description.

In this drawing: Figure 1 is a fragmentary horizontal section through a portion of 45 a furnace embodying this invention, illustrating a plurality of stoker-boxes or fuel-pushers in their various positions with certain of the parts broken away to more clearly illustrate the construction; Fig. 2 is a fragmentary vertical section illustrating portions 50 of the furnace, including one of the stoker-boxes in section and its operating mechanism, and Fig. 3 is an end view of the crank-shaft by which the stoker-boxes are 55 reciprocated.

Referring to the drawing, it will be ob-

served that a fragment or portion 10 of the fire-box inclined grate is illustrated and above this, parts of the double-arch 11 and 12 are also shown. Extended lengthwise of each side of the furnace is a fuel-magazine 13 having an open bottom or discharge mouth above a sectional coking-plate 14, that portion of which adjacent to the firebox of the furnace is equipped with an air-flue 15 beneath it through which cooling air is drawn into the furnace, such air acting to prevent damage to the coking-plate and also supplying at least a portion of the oxygen for effecting the combustion of the fuel. On 70 this sectional dead-plate or coking-plate 14 I employ a plurality of stoker-boxes or fuel feeders 16, 17, 18, 19, 20, and 21, each of which is hollow and rests upon the coking-plate as illustrated in Fig. 2 so that by its 75 reciprocation transversely of the furnace and in conjunction with the discharge of fuel from the magazine, it slowly and gradually pushes the fuel resting on the coking-plate ahead of it over the edge of the latter 80 and on to the top portion of the grate. It is desirable to make this feed of coal continuous, and to effect this result, I so construct the operating-mechanism that when some of the stoker-boxes are receding others 85 are advancing, and while the latter are backing, the former are moving forwardly, securing a substantially continuous feed of fuel to the grate. To accomplish this result, in this particular embodiment of the invention, I employ a crank-shaft 22 relatively 90 slowly revolved in any approved manner by mechanism not illustrated. This shaft has several crank-portions 23, 24, 25, and 26, and each of the stoker-boxes in its interior 95 is equipped with two pairs of braced spaced lugs 27 and 28, each pair of which receives between them the upper-end 29 of an arm 30, the widened portion 31 of which is apertured at 32 for the accommodation of one of the 100 crank parts of the shaft. These various rock-arms 30 are fulcrumed at 33 on suitable depending brackets and the opposite sides of their upper ends 29 are curved so as to secure a rocking-action on the faces of the companion lugs or wings 27 and 28.

Assuming that the shaft 22 is slowly revolving in a clockwise direction as viewed from the front of the furnace, that is, from the bottom of Fig. 1, the stoker-box 16 is 110 at the extreme end of its inward stroke, pusher 17 is midway of its rearward travel,

fuel-pusher 18 is at the end of its backward movement and is just about to begin its forward travel, stoker-box 19 is midway of its forward movement, and boxes 20 and 5 21 are in positions corresponding to those of the elements 16 and 17, or stated differently, the successive crank-portions of the shaft 22, which are 90° apart, are in operative association with the successive 10 stoker-boxes, which, as is clearly illustrated, are disposed end to end, are independent of one another, and have their own movements determined by the various parts of the 15 crank-shaft. In this way, a substantially continuous and automatic feeding of the fuel to the grate over the coking-plate is obtained.

Although I have illustrated this invention as incorporated in a furnace of the Murphy 20 V-grate type with fuel reservoirs or magazines at its sides, it is to be understood that the invention is in no way limited to such particular employment and that it is susceptible of use in furnaces of widely differing 25 constructions, nor is the invention limited to the precise and exact structural features illustrated and described, because these may be varied within comparatively wide limits without departure from the substance 30 of the invention and without the sacrifice of any of its substantial benefits and advantages.

I claim:

1. In an automatic furnace stoking device 35 of the character described, the combination of a fuel-magazine, a coking-member adapted to receive fuel from said magazine, an inclined grate in association with said coking-member and adapted to receive the fuel 40 at its upper-portion from the coking-member, a plurality of groups of independent fuel-pushers arranged end to end in a direct uninterrupted series and adapted to feed the fuel from the magazine across the 45 coking-member on to the grate, and means

to operate the pushers of each group continuously causing the pushers of each group at all times to occupy successively different positions in their strokes, effecting a substantially continuous fuel feed from the 50 magazine across the coking-member to the grate, substantially as described.

2. In an automatic furnace stoking device of the character described, the combination of a fuel-magazine, a coking-member adapted to receive fuel from said magazine, an inclined grate in association with said coking-member adapted to receive the fuel at its upper-portion from the coking-member, a plurality of groups of independent fuel-pushers arranged end to end in a direct uninterrupted series and adapted to feed the fuel from the magazine across the coking-member on to the grate, a crank-shaft with 55 crank-portions disposed at different angles, and means connecting the crank-portions of said shaft to said pushers and adapted to operate the pushers of each group continuously causing the pushers of each group at all times to occupy successively different 60 positions in their strokes, effecting a substantially continuous fuel feed from the magazine across the coking-member to the grate, substantially as described.

3. In an automatic furnace stoking device 75 of the character described, the combination of a fuel-magazine, a coking-plate, a grate, a plurality of independent fuel-pushers arranged end to end in a direct uninterrupted 80 series, a revolvable shaft having crank-portions disposed at different angles, and means operatively connecting such crank-portions to the various individual pushers, whereby to secure independent reciprocations of the latter across the coking-plate and substantially continuous fuel feed from the magazine across the coking-plate to the top of the grate, substantially as described.

FRANK B. BIGELOW.
